UNITED STATES PATENT OFFICE.

WILSON HEMINGWAY, JR., OF VICKSBURG, MISSISSIPPI, ASSIGNOR TO THE ELECTRO-
LOCK MANUFACTURING COMPANY, OF VICKSBURG, MISSISSIPPI, A CORPORATION
OF MISSISSIPPI.

COIL CASING AND SWITCH THEREFOR.

Application filed March 1, 1923. Serial No. 622,205.

This invention relates to systems of electrical distribution now used on automobiles, motor boats and the like, and is an improvement or continuation in part of the broad conception and subject matter disclosed by me in copending application filed December 20th, 1922, and bearing Serial Number 608,055.

The principal object of the present invention is to provide efficient means for preventing unauthorized use or removal of the coils and other parts of the transformer assembly, commonly embodied in systems of the above mentioned type.

15 A more specific object of the invention is to utilize a controlling switch of the type disclosed in said copending applications, in combination with a coil box or casing, to render the transformer assembly inaccessible when the switch is in locked position, thereby effectively guarding said assembly against theft, unauthorized use and mischievous tampering.

20 Other purposes and advantages of the invention, not specifically stated above, will become apparent from the following detailed description and accompanying drawings wherein I have disclosed what I now consider to be the preferred embodiment of the 30 invention.

In the drawings:

Figure 1 is a vertical, sectional view of a coil box and switch constructed in accordance with my invention.

35 Figure 2 is a horizontal sectional view on the line 2-2 of Figure 3, illustrating the arrangement of contacts carried by the movable parts of the switch.

40 Figure 3 is a view partly in elevation and partly in vertical section of the coil box and associated switch.

Figure 4 is a sectional view on line 4-4 of Figure 3, illustrating the arrangement of contacts carried by the stationary part 45 of the switch, the movable contacts being designated by dotted lines as they will appear in the closed position of the switch and the central portion of the view being broken away to expose interior lock structure.

50 Figures 5 and 6 are views similar to Figure 4, illustrating by dotted lines the differ-

ent positions to which the movable contacts are shifted in the use of the switch.

Figure 7 is a diagrammatic view illustrating the manner in which the switch and associated parts of the transformer assembly are embodied in a complete system.

Referring more particularly to the drawings, 5 designates a tubular casing open at one end and provided at an intermediate point with an internal annular shoulder 6. This casing is used to inclose a transformer assembly comprising an induction coil 7, a resistance 8 connected in series with the primary winding of the coil and a condenser 9 having shunt connection with said winding. Preferably the induction coil 7 is fastened by a screw 10 to the closed end of the casing with the primary and secondary 70 windings of the coil secured to the low and high tension terminals 11 and 12.

In order to prevent removal, tampering with, or unauthorized use of the said transformer assembly, I provide a suitable switch 75 structure adapted to be secured in the open end of the casing 5 to provide a closure therefor which cannot be removed in the locked position of the switch except by breakage. The switch structure which I use in this 80 connection is, with the exception of a few changes, substantially the same as that disclosed in my copending application Serial Number 608,055, filed December 20th, 1922, and therefore in describing such structure, 85 detailed reference will be had only to such parts thereof as are necessary to the purposes of the present invention.

As herein disclosed, the said switch structure comprises a base 13 formed of insulating material and of a size to be snugly received within the open end of the casing 5. This base is equipped with a central sleeve or bushing 14, the inner end of which is formed with an integral flange 15 having a 95 circumference equal to that of the base and being adapted to rest against the seat 6 to which it is secured by suitable screw bolts 16. The heads of the bolts 16 are concealed between the flange 15 and the base 13, the 100 inner surface of the latter being preferably cut away to provide recesses 17 accommodating the heads therein.

An annular wall or shell 18 is suitably

secured to the outer circumferential edge of the base 13 and is equipped with an in-turned flange 19 to which the cover 20 of the switch is rotatably secured preferably by means of a retaining ring 21, fastened to the inner side of the cover and projecting over the inner surface of the flange. Movement of the cover in either direction is preferably limited by means of a projection 22 carried by the cover and operating in a slot 23 formed by cutting away a portion of the flange 19, this construction being clearly illustrated by dotted lines in Figure 2.

The cover 20 is also provided with a central opening in which is keyed the upper end of a lock barrel 24. The lower end of this barrel is rotatably mounted in the bushing or sleeve 14 and a locking mechanism inclosed within the barrel, preferably includes a bolt 25 adapted to be projected outwardly through suitable openings in sleeve 14 and selectively engaged with a pair of recesses or sockets 25' and 25'' formed in the base 13 when the cover is rotated to predetermined positions.

Numerals 26 and 27 indicate a pair of contact brushes electrically connected together through the medium of a bar 28 formed of a suitable conducting material. This bar is secured to the inner side of the cover by suitable screws 29 as shown to advantage in Figure 2. The cover also carries a pair of contact fingers 30 and 31 secured together at their upper ends and to the cover through the medium of a screw 32. A further contact finger 33 is fastened to the conducting bar 28 intermediate the main contacts 26 and 27. The base 13 of the switch is equipped with a plurality of contacts designated respectively 34, 35, 36, 37, and 38, the contact 36 being connected through the resistance 8 to the primary winding of the induction coil 7 as shown to advantage in Figure 1.

In practice, the switch and transformer assembly carried by the casing 5 are incorporated in a system of distribution as shown to advantage in Figure 7.

As shown in this figure, the main contact 34 of the switch base 13 is connected by a lead 39 to one terminal of the battery 40, the remaining terminal of the battery being connected to the ground. The opposite contact 35 of the switch base is connected through the starter switch 41 to the starter 42. The stationary contact 38 of the switch base is connected by suitable leads to the ammeter 43 and to the movable elements of the light switch 44 and ignition switch 45, the stationary contact of the latter switch being connected by a return lead 46 to the stationary contact 37 of the switch base. In the closed position of my improved switch, as represented in Figure 4, the main cover contacts 26 and 27 are engaged with the

main base contacts 34 and 35, while the contact fingers 30, 31 and 33 are in engagement with the base contacts 36, 37 and 38. Current is therefore permitted to flow from the battery through the contacts 34, 26, contact bar 28 and contacts 27 and 35 to the starter switch. Current is also supplied through the bar 28, engaged contacts 33 and 38 and the ammeter 43 to the movable contacts of the lighting and ignition switches. When the ignition switch 45 is closed the current passes from the stationary contact of said switch to the contact 37 through the contact fingers 30 and 31 to the contact 36 and from the latter to the primary winding of the induction coil 7. As represented diagrammatically, the low tension terminal 11 of the coil is connected to an interrupter 47 while the high tension terminal 12 is connected to the distributor 48. In this position of the main controlling switch, it is evident that current may be supplied at will to the starting, lighting and ignition circuits by closing the switches 41, 44 and 45. When it is desired to shut off the flow of current to the starter and ignition circuits without interfering with the lighting circuits, the movable contacts of the main controlling switch are shifted to the first off position represented by Figure 5. As shown in this figure, the movable contact 27 has passed out of engagement with the stationary base contact 35 but the movable contact 26 is still permitted to remain in engagement with the base contact 34, due to the fact that the last mentioned contact is made somewhat longer than the contact 35. In this position of the parts, current from the battery flows through contact 34, connecting bar 28 and contact finger 33 to the contact 38 and from thence through the ammeter 43 to the movable contact of the lighting switch 44. No current, however, is furnished to the ignition switch due to the fact that the ignition circuit has been disrupted by separation of the contact fingers 30 and 31 from the contacts 36 and 37. The switch is locked in this position by projection of the bolt 25 through one of the openings of the sleeve 14 and into the socket 25' of the base.

When it is desired to cut off all flow of current from the battery, the movable switch contacts are shifted to the position shown in Figure 6 and in this position, it will be noted that the movable contacts 26 and 33 have been entirely disengaged with the stationary contacts 34 and 38 so that all circuits leading to the battery are disrupted. In this position the switch is locked by projection of the bolt 25 into the socket 25'' of the base.

In order to prevent unauthorized use of the generator, designated by the numeral 49, the insulated terminal thereof is connected through the ammeter 43 to the movable

contact of the ignition switch 45. It will thus be seen that, in the open position of my improved switch, no current from the generator is permitted to pass to the ignition and starting equipment.

From the foregoing, it will be apparent that my invention affords simple and effective means for protecting the electrical equipment of an automobile, motor boat, or 10 the like, against unauthorized use and the injurious effects of grounds or short circuits such as frequently develop in the wiring. The invention also serves to prevent theft of the coils and other parts of the 15 transformer assembly by inclosure of the assembly in a casing which cannot be opened, in the locked position of the switch, except by completely destroying the same. With 20 reference to this last statement it is pointed out that, in the locked position of the switch, the bolt 25, by reason of its projection through an opening of the sleeve 14, serves to lock the barrel 24 and the cover 20 to said sleeve and as the latter is anchored to 25 the casing 5 by concealed fastening bolts 16 removal of the switch structure from the opening of the casing 5 is effectually prevented. In the unlocked position of the 30 switch, the cover 20 and the base 13 may be easily removed to expose the screws 16 which may be then withdrawn to release the sleeve 14. In assembling the switch structure with casing 5 the flange 15 is first secured in place by the screws 16 and the sections of the base element 13 then placed in 35 position. Shell 18 may be fastened or held to the base 13 in any suitable manner it being understood that the cover 20 is secured to the flange 19 by the retaining ring 40 21 prior to assembly of the shell 18 with the base 13.

By inclosing the resistance 8 with the induction coil 7, I avoid the exposure of any terminals connected directly to the coil which 45 could be utilized by unauthorized persons for supplying current to the coil independently of the contacts carried by the switch box 13. The condenser is preferably made as a part of the coil and inclosed therewith 50 to insure a uniform condenser circuit perfectly balanced with the coil on which it is to be used. In this way, the possibility of condensers being used with coils for which they are not particularly designed is reduced to a minimum.

Having thus fully described what I now conceive to be the preferred embodiment of my invention, it is to be understood that I am not to be limited to the exact construction and assemblage of parts set forth, as 60 various changes and modifications may be resorted to within the scope and spirit of the appended claims.

I claim:

1. A combined housing and control switch

for electrical apparatus comprising a metal casing formed with a single opening for insertion and removal of said apparatus, a switch inserted in said casing and including a rotary cover closing said opening, and 70 means for locking said cover in various circuit controlling positions including provision for securing said cover and the other components of the switch structure against removal from the casing. 75

2. A housing for electrical apparatus comprising a casing formed with a single opening for insertion and removal of said apparatus, said casing being formed with an interior annular shoulder located inwardly 80 of and facing toward said opening, a switch structure including a base portion seated against said shoulder and a rotary cover portion assembled with the base portion and made of a size to form a closure for said 85 opening and means for locking the cover and base portions of the switch together in a predetermined circuit controlling position including provision for securing the said locked-together portions of the switch 90 directly to the casing to prevent removal of the switch.

3. A housing for electrical apparatus comprising a casing formed with a single opening for insertion and removal of said apparatus, an inserted switch including a base portion having an element thereof anchored to the casing, a cover portion rotatably assembled with the base portion and arranged to close the opening in the casing and to 100 conceal said base portion, said cover and base portions of the switch being provided with cooperating circuit controlling contacts and means for locking the cover portion of the switch to the anchored element 105 of the base portion when the cover portion is moved to a predetermined circuit controlling position.

4. A housing for electrical apparatus comprising a casing formed with a single opening for insertion and removal of said apparatus, an inserted switch arranged to form a closure for said opening and provided with a base portion having a centrally located metal sleeve fastened to a wall portion of the casing, a cover portion rotatably assembled with said base portion, a lock barrel having its outer end fixed to the cover portion to rotate therewith and its inner end extending into said sleeve, said lock 110 barrel enclosing a locking mechanism including a bolt adapted to be projected through an opening in the sleeve and into a socket formed in the base portion. 115

5. A housing for electrical apparatus comprising a casing formed with a single opening for insertion and removal of said apparatus, an inserted switch arranged to form a closure for said opening, said switch comprising a base of insulating material, a 120 125

metal sleeve extending centrally through said base and provided at one end with a metal flange, fastening means securing said flange to a wall portion of the casing and arranged to be concealed by an overlying portion of the base, a cover rotatably assembled with said base, said cover and base being provided with cooperating circuit controlling contacts, a lock barrel having one end keyed to the cover to rotate therewith and the other end extending into said sleeve, and a lock mechanism within said barrel including a bolt adapted to be projected through an opening in the sleeve.

15 6. A housing for electrical apparatus comprising a casing formed with a single opening for insertion and removal of said apparatus, an inserted switch including a base portion and a cover portion, the latter being rotatably mounted in the opening of the casing and arranged to form a closure for said opening, said cover and base portions being provided with cooperating circuit

controlling contacts, and means for locking the cover in a predetermined circuit controlling position including provision for securing the cover to an interior wall portion of the casing whereby removal of the cover and other components of the switch structure is prevented.

25

7. A housing for electrical apparatus comprising a casing formed with a single opening for insertion and removal of said apparatus, a switch inserted in the casing and arranged to close said opening, said switch including a part fastened to an interior wall portion of the casing and a second part adapted to be locked to the first mentioned part in certain predetermined position of the removable element of the switch and to thereby secure the complete switch structure against removal from the casing.

30

In testimony whereof I have hereunto affixed my signature.
